UNITED STATES PATENT OFFICE.

WILLIAM BEACH ERSKINE, OF NEW YORK, N. Y., ASSIGNOR TO AMERICAN AUTOMATIC LOOM COMPANY, OF SAME PLACE.

LOOM.

SPECIFICATION forming part of Letters Patent No. 669,916, dated March 12, 1901.

Application filed November 22, 1900. Serial No. 37,369. (No model.)

To all whom it may concern:

Be it known that I, WILLIAM BEACH ERSKINE, a citizen of the United States, and a resident of No. 138 West One Hundred and 5 Twenty-second street, in the borough of Manhattan, city, county, and State of New York, have invented a new and useful Improvement in Looms, of which the following is a specification.

10 My invention relates to narrow-ware looms, and more particularly to that type known as "needle-looms," wherein the filling is inserted by means of filling-inserting needles which are reciprocated through the sheds to lay the 15 filling in the form of loops and the loops when laid are held by vertically-reciprocating loop-engaging needles, which are withdrawn from the loops at the time of the beat-up, so as to free them at that time to the action 20 of the reed. A needle-loom of this kind is set forth, for example, in Kuett's patent, No. 653,249, dated July 10, 1900.

25 My invention relates to the devices for operating the vertically-reciprocating loop-engaging needles.

It is my object to provide for this purpose a simple and efficient mechanism which is susceptible of ready application and adjustment and will facilitate the operation of 30 changing over other types of narrow-ware looms to the needle type.

To this end my invention consists of the parts and combinations, as will be hereinafter more fully described, and definitely pointed 35 out in the claims.

In the drawings, Figure 1 is a side view of so much of a loom—including the batten, vertical needle-operating appliances, and a portion of the supporting-frame of the loom—as 40 needed for the purpose of illustrating and explaining the invention. In this figure the central portion of the reed-frame is broken away and the upper portion brought down. Fig. 2 is a sectional side elevation of the bat- 45 ten, the vertical needle-frame and one of the needles, and the rock-shaft and connections between the same and said frame.

1 is the batten or lay, which is to be mounted and actuated from the main shaft 2 of the 50 loom in the usual way. The devices for this purpose are well known to those acquainted

with the art to which my invention pertains and require no illustration.

In the top of the batten is the usual longitudinal groove 3, in which the reciprocatory carrier slides for the horizontal filling-inserting needles are received and held. I omit also illustration of these carriers as unnecessary to an understanding of the invention.

Mounted on the lay in any usual manner 60 is the reed-frame 4, which may be formed in as many sections as desired corresponding to the number of fabrics desired to be woven at any one time.

Mounted upon the rear face of the lay is 65 the vertically-reciprocating frame, which carries the upright loop-engaging needles. The frame consists in this instance of two longitudinal rigid bars 5, secured at their ends to sleeves 6, which fit around and are adapted 70 to slide up and down upon guide-rods 7, fastened in brackets 8, attached to the lay.

75 The vertical loop-engaging needles, one of which is shown at 9, are mounted on the frame-bars 5 in any proper way, being so mounted and constructed that while all of them rise and fall with the frame, yet each will be individually capable of yielding toward the reed and the edge of the warp, as set forth in the Kuett patent, No. 653,249, above referred 80 to. The needle 9 for this purpose is represented as mounted in a bracket 10, as described and illustrated in said patent.

85 Mounted in hangers 11, secured to the bottom of the lay, is a rock-shaft 12, which extends beneath and lengthwise of the lay and has projecting from it at intervals throughout its length radial arms 29, rigidly secured to it by set-screws or other suitable means. These arms project to the rear and at their 90 outer ends are jointed at 14 to links 13, which in turn are jointed at 15 to the vertical needle-carrying frame. In this way a rocking movement of shaft 12 will produce an up-and-down movement of the vertical needle-carrying frame. Counterbalance-weights 16 95 or their equivalents may be secured to or mounted on shaft 12, as shown, so as to counterbalance the weight of the needle-carrying frame.

100 Rock-shaft 12 is actuated from the main shaft 2 of the loom by suitable connections.

The devices for this purpose shown in the drawings consist of an arm or rod 17, rigidly secured at one end to the rock-shaft and at the other end engaging a crank-pin 18 on shaft 2, the crank-pin entering a longitudinal slot 19 in the rod 17. The purpose of this slot is to maintain the crank-pin in engagement with the rod 17 without interfering with the back-and-forth movement of the lay. The crank-pin has on it an antifriction-bushing or roller-sleeve to reduce friction. The rod 17 is preferably a two-part rod, the overlapping meeting ends of its two parts being provided with a series of holes 20 to receive the bolts and nuts 21, by which they are held rigidly together. By this means the working length of the rod can be adjusted to the distance between the main shaft and the lay in the particular loom to which the lay containing my improvements may be applied. The crank-pin 18 is adjustable both to and from the axis of the main shaft and also around said shaft. The former adjustment serves to regulate the throw of the crank, and consequently the extent of rocking movement of shaft 12, or, in other words, the extent of reciprocatory movement of the vertical needles. The latter adjustment is for the purpose of timing this movement of the said needles relatively to that of the lay and of the horizontal filling-inserting needles. To this end the crank-pin 18 is secured in a carrier 22, which is adjustable on shaft 2 and is provided with a slot 23, radial to the shaft, in which slot the crank-pin is seated and can be adjusted and held at any desired distance from the axis of the shaft. The carrier 22 itself can be moved around the axis of the shaft, being for this purpose preferably mounted so as to turn upon a center 24, coincident with the axis of the shaft, and it is held in the position to which it may be adjusted by a set-screw 25 or its equivalent with which it is provided, which enters and engages a slot 26 in a plate 27, secured to the shaft 2 or the drive-wheel 28 thereon, said slot being curved to conform to the arc of a circle struck from the point 24 as a center. In this way the two adjustments can be readily and accurately made.

My invention possesses marked advantages on the score of efficiency, economy, and simplicity over prior devices used for the purpose. There is a marked saving of power, friction, and vibration, less wear and tear on the loom, and the loom can be run at a higher speed without injury. An even greater advantage is the saving of cost and time in changing over narrow-ware looms to this system. Under my invention the entire change in construction is in the lay and its appurtenances. The lay with all its parts and the vertical needle-frame and all its operating appliances can be made in the machine-shop

and can then be set up in place in the loom 65 without any change in the loom proper, all that is needed after the lay is in place in the loom being to adjust the length of the slotted rod 17 to the distance between the main shaft and the lay and to put the crank-pin carrier 70 22 and the slotted plate 27 in place on the main shaft and after adjusting the crank-pin so as to obtain the proper throw and timing to secure it in that adjusted position.

Having described my invention and the best 75 way now known to me of carrying the same into effect, I state, in conclusion, that I do not confine myself narrowly to the structural details hereinbefore set forth, since manifestly they can be varied to a considerable extent 80 without departure from the invention; but

What I claim, and desire to secure by Letters Patent, is—

1. In a needle-loom, and in combination with the lay and main shaft, a vertically-reciprocatory loop-engaging-needle frame mounted on the lay, a rock-shaft mounted on and carried by the lay lengthwise of the same, connections between said rock-shaft and said frame whereby the rocking movement of said shaft causes the reciprocatory movement of said frame, a slotted arm or rod rigidly fixed to the rock-shaft, and a crank-pin on the driving-shaft engaging the said slotted arm, substantially as and for the purposes 95 hereinbefore set forth.

2. In a needle-loom, and in combination with the lay and the main shaft, a crank-pin carried by the driving-shaft and adjustable both to and from, and around, the axis of said 100 shaft, a vertically-reciprocatory loop-engaging-needle frame mounted on the lay, a rock-shaft mounted on and lengthwise of the lay, and operatively connected to the loop-engaging-needle frame, and connections between 105 the rock-shaft and crank-pin whereby the rock-shaft is positively actuated in both directions, substantially as and for the purpose hereinbefore set forth.

3. In a needle-loom and in combination 110 with the main shaft and lay, a vertically-reciprocatory loop-engaging-needle frame mounted on the lay, a rock-shaft mounted on and lengthwise of the lay and operatively connected to said frame, a crank-pin carried by 115 the driving-shaft and adjustable relatively thereto, and a slotted two-part arm rigidly fixed to the rock-shaft and engaging the crank-pin, and adjustable in length, substantially as and for the purpose hereinbefore set 120 forth.

In testimony whereof I have hereunto set my hand this 16th day of November, 1900.

WILLIAM BEACH ERSKINE.
